UNITED STATES PATENT OFFICE.

JOHN W. WINTERBOTTOM AND RALPH F. WINTERBOTTOM, OF WATERLOO, IOWA.

HEATING APPARATUS.

Application filed April 17, 1922. Serial No. 554,101.

To all whom it may concern:

Be it known that we, JOHN W. WINTERBOTTOM and RALPH F. WINTERBOTTOM, both citizens of the United States of America, and 5 both residents of Waterloo, Black Hawk County, Iowa, have invented certain new and useful Improvements in Heating Apparatus, of which the following is a specification.

10 Our invention relates to improvements in heating apparatus, and particularly to radiators adapted for both direct and indirect radiation of heat, whether by direct radiation from exposed surfaces or by indirect 15 heating by conduction to a current of air in circulation through the apparatus.

One object of our improvements is to supply heating and ventilating unit elements of hollow and communicating construction, for 20 steam, vacuum, vapor or hot water heating as desired, the outer surfaces of the assembled units being effective within a room for direct radiation of heat thereinto, and inner passages within the convolutions of 25 said units serving to conduct therethrough air under artificial or natural pressure, heating this air by conduction before delivering it warmed into the air of the room.

Another object is to use the apparatus as 30 a re-heater by passing through it air under pressure which has been previously initially heated by heating means at a remote location.

Another object of our improvements is to 35 so position air-receiving and air-delivery vents of said apparatus as to receive air from the room adjacent the floor thereof and to deliver warmed air at the top of the apparatus in order to effect proper and natural 40 circulation of air within the room by first withdrawing the colder air nearest the floor.

Another object is to provide the apparatus with a by-pass controlled by a suitable valve, for diverting a portion of the air-supply 45 from the central heating passages when it is found desirable to adjustably vary the temperature of the warmed air delivered into the room.

These objects have been accomplished by 50 the means which are hereinafter described and claimed, but it is to be understood that various modifications may be effected in the details of the construction of the apparatus without departing from the principles of the invention, or the proper protection thereof.

In the drawings, Fig. 1 is a view, partly in front elevation and partly in section, of assembled radiator units of our improved heating apparatus. Fig. 2 is a vertical transverse section of this apparatus including air-pressure and primary heating means, with parts broken away. Fig. 3 is a horizontal section of an end unit and an abutting intermediate unit of the radiator units. Fig. 4 is a perspective view, fragmental, of 60 one of the intermediate radiator units. Fig. 5 is a perspective view of the humidifier or water container. Figs. 6 and 7 are respectively perspective views showing the rear and the front parts of the assembled radiator 70 units.

The improved radiator of our heating apparatus is made up of a desired number of intermediate units 1 placed between and assembled with end units 2, all said unitary 75 elements being hollow intercommunicating structures made of any suitable material and of dimensions and proportions to suit any exigency.

Each end element 2 has at top and bottom the orificed seats 39 and 7 respectively containing the nipples 40 and 8, as in ordinary radiator practice, the upper ones constituting a horizontal passage to receive a 80 fluid heating medium such as steam from a source of supply and deliver it into the upper part of the hollow of each of the sections 2 and 1, so that the steam after transversing the different channels therein may be delivered from the lower passage to 85 a conduit not shown for evacuation exterior of the apparatus and room.

Each of the intermediate sections or hollow elements 1 of the radiator comprises 90 hollow uprights 1 and 5 connected by spaced 95 sloping transverse conduits connected by webs 6 and each conduit is made up of diminished end parts 4 and an enlarged middle part 3, the latter preferably but not necessarily of diamond shape cross-section 100 to increase its exterior radiating surface. The upper ends of the risers 1 and 5 are in communication with a relatively large cavity 12 in the upper part of the radiator, and between the elements 1 and 2 a number 105 of ports 9 and 10 are respectively provided in the back and front of the radiator to serve as air-ports. Several cross-rods 36 are fixed across the cavity 12 and upon them is supported removably a water-container 110

37 being an open top tank. This tank is preferably but not necessarily shaped with an elongated inner inversion 38 of its bottom, thus supplying a larger surface for the conduction of heat into the water content. 5 Porous filtering material 41 is held below the ports 10 by screening netting 42.

Below the radiator and communicating therewith by way of ports 14 and 15 respectively are upper and lower compartments or air-distributing chambers 13 and 19. An air-insulated by-pass 16 or more than one, is positioned back of the radiator and may be received in a recess in the wall 15 part 17, the upper part of the by-pass delivering into said cavity 12 through the ports 9. The lower end of the by-pass communicates with the upper distributing chamber 13, the communication being controlled adjustably or closed by means of a rock-valve or damper 18.

Opposite each other in the rear and front walls of the lower distributing-chamber 19 are openings 22 and 21 respectively independently closed or adjustably variably opened by valves 26 and 23, but these valves may be operated by means of a single slide-rod and link connections 20 and 25 or 24 as shown.

30 A rotary fan-blower may be installed within the lower compartment 19 if desired, but when the apparatus is to be such as to have a rotary blower delivering air under pressure to a number of radiators, as in an 35 apartment house or other building, such blower may be located at a remote distance in another room. As shown in said Fig. 2, this arrangement is illustrated, wherein the rotary blower 29—30 is mounted in a housing 28 in another apartment, said housing having communication by way of a conduit 27 with the receiving opening 22 of the chamber 19. The housing 28 may have a communicating extension 31 containing a 40 pre-heating coil 32 for initially heating to a desired temperature air received through the open end of the extension, said end being 45 traversed by a reticulated screen 33. Within said extension end may be mounted rock- 50 ing valves 34, to be actuated manually by a shifting-device 35 to regulate entrance of fresh air.

The valve 18 may be opened to a desired amount to divert a portion of air from the 55 distributing-chamber 13 from the passages of the radiator to the by-pass 16, thence to the cavity 12 to mix with the heated air arising thereinto from the radiator passages, thus tempering the air delivered into the 60 room through the vent-openings 10. This air also delivers into the room a sufficient amount of vapor from the contents of the container 37.

The lower valves 23 may be completely 65 opened while the other valves 26 are closed,

to thereby induce circulation of air in the room, for it will be observed that hot air delivered at the top of the radiator will enter the room and push before it the colder air adjacent the floor and into the opening 70 21. This creates a complete and diffused movement of air through the room, without unpleasant drafts, ventilating and humidifying the room thoroughly. In practice, as shown in said Fig. 2, the valves 26 and 23 75 are both left partly open, as the forced air supply from the blower 29 accelerates and increases the fresh warmed air circulation in the room, a necessary desideratum in rooms occupied by a number of persons. 80

It will be observed that as the hollow radiator elements 1 are uncased, their outer surfaces give a direct radiation of heat to the exterior air in the apartment at all times, during, and regardless of whether the 85 air moving up through the air-passages of the radiator is under forced or natural draft.

As the transverse parts 4—3 of the radiator elements are substantially horizontal and of relatively large radiating surfaces, ascending air in the passages is baffled thereagainst and by the webs 6, to effect quick and maximum heating, and the parts 4—3 are preferably staggered in the alternated elements 1, to provide winding passages, enhancing the heating of the air while in the radiator. As the parts 4—3 are slightly sloped, water of condensation is 95 quickly delivered to the lower conduit for 100 evacuation.

A small dead-end steam-tube 43 is seated in the lower steam conduit of the radiator, with the end perforation 44 to exhaust 105 its air, and is used to keep the base of the radiator warm. This is necessary when the main supply of steam is shut off, and prevents freezing of water of condensation. Doors 46 give access to the cavity 12 for 110 insertion or removal of the container 37. 110

Having described our invention, what we claim as new, and desire to secure by Letters Patent, is:

1. In heating apparatus, a distributing chamber in communication with a controllable source of air under pressure, hollow radiator elements assembled together and in circulatory communication with each other and with a source of fluid supply under pressure and with a desired temperature, hollow air-conduit elements assembled with said radiator elements in communication at one end with said distributing chamber and having delivery vents at the other end, a by-pass leading from said distributing chamber into the communicating parts of the air-conduit elements adjacent said delivery vents, means for controlling adjustably said by-pass, said distributing chamber also having controllable means of 115 120 125 130

- communication with the surrounding atmosphere, and said radiator elements being of winding shape with their inter-winding spaces in communication with said air-³⁵ duct elements.
2. In heating apparatus, a radiator having cavities in communication with a heating agent and having other cavities in communication with a source of air supply, and ¹⁰ a conduit of relatively small diameter for a heating agent traversing the basal part of the radiator, and having a small terminal air-exhausting vent.
3. In heating apparatus, in combination, ¹⁵ a plurality of uninclosed sets of hollow spaced upright conduits for a heating fluid in communication at opposite ends with a supply-pipe and a discharge-pipe respectively, said sets of conduits having an impermeable joint between them to inclose an interspace open at both ends to contain a fluid to be heated, and cross-conduits ²⁰ connecting the upright conduits of each set in spaced relation.
- 25 4. In heating apparatus, in combination, a plurality of sets of uninclosed hollow spaced upright conduits for a heating fluid in communication at opposite ends with a supply-pipe and a discharge-device respectively, the abutting sets of conduits having impermeable spaced longitudinal joints, cross-conduits in communication with the upright conduits of each set, the conduits ³⁰ being connected by imperforate webs, and
- their interspaces between said joints open at opposite ends to the atmosphere.
5. In heating apparatus, in combination, a plurality of sets of uninclosed hollow spaced upright conduits for a heating fluid in communication at opposite ends with a ⁴⁰ source of supply and with a discharging device respectively, the abutting conduits having impermeable spaced longitudinal joints, and cross-conduits in communication with the upright conduits of each set and ⁴⁵ connected by imperforate webs, the cross-conduits of each set being staggered with relation to the cross-conduits of abutting sets, and the ends only of their interspaces between said joints open to the atmosphere. ⁵⁰
6. In heating apparatus, in combination, a plurality of uninclosed sets of hollow spaced upright conduits for a heating fluid in communication at opposite ends with supply- and discharge-means respectively, ⁵⁵ the abutting sets of conduits having impermeable spaced longitudinal joints, and cross-conduits in communication with the upright conduits of each set and connected by imperforate webs, the cross-conduits ⁶⁰ being inclined and each having one part enlarged, and the ends only of their interspaces open to the atmosphere.

Signed at Waterloo, Iowa, this 15th day of April, 1922.

JOHN W. WINTERBOTTOM.
RALPH F. WINTERBOTTOM.
